UNITED STATES PATENT OFFICE

2,116,121

APPARATUS FOR COILING MATERIAL

Alonzo B. Montgomery, Youngstown, Ohio, assignor to The Cold Metal Process Company, Youngstown, Ohio, a corporation of Ohio

Application December 21, 1935, Serial No. 55,662

6 Claims. (Cl. 242—78)

This invention relates to apparatus for coiling material and, in particular, to a coiling reel adapted to receive hot strip material and coil it within a heating furnace as it emerges from a rolling mill. This general combination of apparatus is disclosed in United States patent to Steckel No. 1,977,214.

Coiling reels for applications of the character mentioned have been made heretofore by disposing a pair of discs on a shaft and welding thereto blades extending parallel to the shaft. Certain difficulties were encountered in the use of such reels. In the first place, it is sometimes necessary to stop the reel for a considerable period and in such event, the blades on different portions thereof are heated to different temperatures since the furnaces are fired from below. The resulting unequal expansion of the blades has introduced internal stress and has actually caused joints between the blades and the discs to be fractured. Another objection was that it was difficult to prevent the insulating material disposed around the shaft from sifting out at the joint between the discs and a protective sleeve surrounding the shaft.

I have invented a coiling reel which successfully overcomes the aforementioned objections, and in addition, is characterized by further novel and useful features. In accordance with my invention, I position a pair of hubs in spaced relation on a supporting and driving shaft. I mount discs on the hubs in driving relation therewith. A protective sleeve extends from one disc to the other and is tightly secured to both. Blades extend axially between the discs and are secured to the outer sides thereof by connections permitting free expansion and contraction of the blades and the removal of any one blade independently of the others. For a complete understanding of the invention, reference is made to the accompanying drawings illustrating a present preferred embodiment.

In the drawings:

Figure 1 is a longitudinal sectional view through a coiling reel in accordance with the invention;

Figure 2 is a transverse sectional view along the line II—II of Figure 1; line I—I of Figure 2 indicates the plane on which the section of Figure 1 is taken;

Figure 3 is a transverse sectional view through one of the blades;

Figure 4 is a view similar to Fig. 1 showing a modified form of the invention;

Figure 5 is a sectional view along the line V—V of Figure 4;

Figure 6 is a view similar to Fig. 3 showing the construction of the modified form; and

Figure 7 is a sectional view showing a portion of Fig. 4 to enlarged scale.

Referring now in detail to the drawings, the side walls of a furnace of any suitable type are indicated at 10. The furnace may be such as that shown in the Steckel patent above mentioned. A shaft extends through the side walls 10 and is journaled in suitable bearings outside of the furnace (not shown). The shaft is preferably arranged to be driven, for example, in the manner shown in the patent referred to. Hubs 12 and 13 are disposed on the shaft 11 in spaced relation and are keyed thereto. Discs 14 and 15 are mounted on the hubs 12 and 13. The discs and hubs have interfitting projections such as teeth and slots 16 and 16' whereby to provide driving connections therebetween. A tubular sleeve 17 surrounds the shaft 11 and extends between the discs 14 and 15, being secured to the hub portions 14' and 15' thereof. The space between the shaft 11 and the sleeve 17 is welded with thermal insulating material 18.

Blades 19 extend between the discs 14 and 15. The blades have end portions 20 disposed at right angles to their length. The body portions are hollow and have openings 21 on the inner sides 30 thereof. One edge of the blades is relatively sharp as shown at 22, while the other edge is rounded. The end portions 20 of the blades are formed into hooks 23 at one side, holes or eyes 24 being formed in the other side.

The discs 14 and 15 have a plurality of projections 25 provided with spaced holes 26 and 26'. The blades 19 are secured to the projections 25 by pins 27 and 28 as shown in Figure 1. The end portions of the blades lie on the outer sides 40 of the discs. Each blade has bosses 25' engaging the edges of the discs to take the collapsing load of the coil winding off the pins.

The pins 27 are permanently secured on the discs as by welding at 29. In applying a blade to the reel, the hooks 23 are first engaged over the protruding ends of the pins 27. The blade is then swung about the pins 27 until the holes 24 are in alignment with the holes 26'. The pins 28 are then inserted and lock the blade in fixed position relative to the discs. The pins 28 are secured in position by cross pins 30 extending through the pins 28 and projections on the end portions 20.

When the blades have all been secured to the discs, the resulting reel is driven so that sharp edges 22 of the blades are leading. If a length of hot strip is then directed substantially radially of the reel, it will enter between two adjacent blades and be bent partially around the second of the two, thus hooking the leading end of the strip secured to the reel for coiling.

It will be clear that the mounting of the blades 10 on the discs permits the former to expand freely and to different extents at different points on the peripheries of the discs. Thus, if the reel remains stationary while the firing of the furnace continues, the lower blades may expand more 15 than the upper blades without introducing any stress whatever into any part of the reel. The blades have a limited free movement axially of the reel since the hooks 23 slide on the pins 27 fixed to the discs, and the pins 28 secured to the 20 end portions 20 of the blades can slide in their holes 28' in the discs. In case of breakage, furthermore, a blade can easily be replaced without disturbing the remaining parts of the reel. This is a marked advantage over the permanently 25 welded construction of the reel previously mentioned. To remove a blade, it is necessary only to knock out the cross pins 30, remove the pins 28, and lift the hooks 23 off the pins 28.

Since the protective sleeve 17 surrounding the 30 shaft between the discs is tightly welded to the latter, the insulation 18 is permanently enclosed in the space between the shaft and the sleeve. The various parts of the reel will preferably be made of heat resistant alloy since it must operate at elevated temperatures, such as 2000° F., when used in the furnace of a hot mill such as that of the Steckel patent.

According to a modification of the structure just described, a shaft 35 is provided with toothed 40 portions 36 and discs 38 having central bores slotted to receive the teeth 36 are disposed on the shaft. The teeth have shoulders 37 against which the discs 38 abut. The discs are held in abutment by rings 39 welded to the shaft. The 45 discs 38 have projections 40 thereon, as in the structure of Figures 1 through 3, and these projections have spaced holes at 41 therethrough. Pins 42 are inserted in the holes 41 and are secured in position by welding, as shown at 43.

Blades 44 similar in general to those shown at 50 19 have lugs 45 extending from points adjacent the ends thereof. The lugs 45 are bored at 46 whereby the blades can be mounted on the discs by alining the holes 46 with the pins 42 and moving 55 the blade axially so that the pins enter the holes. The blades are secured in position by a split ring 47 which seats in an annular groove 48 adjacent the end of the pins 42 on the right-hand disc 38. The halves of the ring 47 are held 60 in place by a holding ring 49 welded thereto. The blades have bosses 50 thereon adapted to engage the edges of the projections 40 for the reason already explained, viz., to relieve the pins of the collapsing load imposed by the winding of a coil 65

of hot strip on the reel composed of the shaft, discs and blades.

By securing the pins 42 firmly to the projections 40, I avoid the possibility of the pins becoming loose in the holes 41 due to the shock and 5 stress normally experienced in the operation of a coiling reel.

The shaft 35 is provided with an enclosing sleeve 17 filled with thermal insulating material 18 as in the structure of Fig. 1. When it is desired to remove one of the blades 44, it is only necessary to knock the locking ring 49 off the split ring 47, and after removing the latter, to shift the blade longitudinally off the pins 42.

Although I have illustrated and described but 15 two preferred forms of the invention, it will be understood that changes in the construction illustrated and described may be made without departing from the spirit of the invention or the scope of the appended claims.

I claim:

1. A coiling reel comprising a pair of spaced discs disposed coaxially, a plurality of blades extending between said discs, said blades having end portions at right angles to their length, said 25 end portions each having an eye and a hook formed therein, the hooks adapted to engage pins permanently secured to the discs and the eyes adapted to receive removable pins passing through the discs.

2. A reel for coiling material comprising a pair of spaced, coaxial discs with blades extending therebetween, hooks on said blades adapted to engage projections on said discs, and removable means securing the blades and discs together to 35 prevent disengagement of said hooks.

3. A reel for coiling material comprising a pair of spaced, coaxial discs with blades extending therebetween cooperating hooks and projections on said blades and discs, and removable means 40 for preventing disengagement of the hooks and projections.

4. A reel for coiling material comprising a shaft, a pair of discs mounted thereon in spaced relation, and a plurality of blades extending between said discs having angularly disposed portions, hooks on said portions removably engaging projections on said discs, and connecting pins extending through said portions and discs whereby the former can expand or contract independently of the latter.

5. A reel for coiling material comprising a pair of spaced, coaxial discs with blades extending therebetween, axial pins disposed peripherally of said discs, hook means on said blades engageable with said pins, and removable means for holding said means in engagement with said pins.

6. A reel for coiling material comprising a pair of spaced coaxial discs, a blade extending therebetween, pins extending axially through the discs, 60 hooks on the blade engaging said pins, and removable pins traversing said blade and discs for securing said hooks in engagement with said first-mentioned pins.

ALONZO B. MONTGOMERY. 64
